UNITED STATES PATENT OFFICE

VICTOR W. I. FREDERICK, OF BROOKLYN, NEW YORK

AIR REGULATOR FOR WINDOW VENTILATORS

Application filed March 25, 1930. Serial No. 438,816.

This invention relates to improvements in air regulators for window ventilators, and for use especially with the type of ventilator shown and described in my copending application Serial No. 386,709, filed August 17, 1929.

The primary object of the invention resides in a regulator attachment by which the entrance of fresh air into a room through my window ventilator may be controlled as it is not possible to adjust the sash of the window to regulate the entrance of air as the said sash is always in tight engagement with the top of the ventilator. It will be appreciated that in cold inclement weather it may not be desirable to admit the maximum amount of fresh air into a room, while at other times it may be desired to completely shut off the ventilator. My regulator attachment is therefore designed to restrict or completely shut off the admission of atmospheric or fresh air through the window ventilator.

Another object is to provide an air regulator embodying a frame adapted to snugly fit into the type of ventilator shown in the above mentioned copending application so as to lie upon the screened bottom thereof, and doors hingedly supported upon the frame for movement to either open or closed positions to regulate the entrance of fresh air through the screen body.

With these and other objects in view the invention resides in the certain novel construction, combination, and arrangement of parts, the essential features of which are hereinafter fully described, are particularly pointed out in the appended claims, and are illustrated in the accompanying drawings, in which:

40 Figure 1 is a vertical transverse sectional view illustrating my air regulator in position upon a window ventilator.

Figure 2 is an enlarged detail sectional view.

45 Figure 3 is a detail perspective view of the air regulator per se, showing the ventilator in dot and dash lines.

50 Figure 4 is a detail perspective view illustrating the manner in which the doors are hingedly mounted in the frame and capable

of being locked or supported in an open position.

Figure 5 is a detail vertical transverse sectional view through the regulator attachment.

Referring to the drawings by reference characters, the numeral 10 designates a window ventilator of the type shown in the above mentioned copending application, and which broadly includes a telescoping imperforate casing 11 provided with downwardly inclined top wall 12, and a reversely inclined perforated or screen bottom wall 13. The construction of this particular window ventilator being clearly shown and described in the copending application, it is not believed necessary to go into detail on the structure and features of the same, although a slight difference exists in the form of ventilator shown in this application wherein the inclined top wall 12 is carried down to provide an overhang or shed 14 for preventing rain water from finding its way down the inclined top wall 12 and onto the screen bottom 13.

In practice, the ventilator is supported within the window frame 15 of a window and held therein by the parting strip and lower sash 16. It is with this type of ventilator that my improved air regulator 17 is adapted for use, and which regulator is placed upon the screen bottom 13 for the purpose of completely shutting off the entrance of air through the screen bottom 13 into a room, or for restricting or regulating the passage of air therethrough.

The air regulator 17 includes a rectangular metal frame 18, the ends thereof being provided with upstanding flanges 19—19 for abutting the end wall of the casing 11 of the ventilator, while the rear side wall is provided with an inwardly and upwardly inclined flange 20 for flush engagement with the inside of the inclined top wall 12 of the ventilator. The front longitudinal side of the frame 18 is provided with a down turned flange 21, which flange snugly fits against the shut portion of the ventilator shown in Figure 1 of the drawings.

From the description thus far it will be seen that the regulator may be snugly fitted

into the ventilator and firmly supported upon the screen bottom 13 thereof.

The frame 18 is provided with a central longitudinal bar 22 which bridges the end rails of the frame and which bar is disposed on the same plane as the ends and sides thereof. Hingedly mounted upon the frame 18 in the end walls thereof, are doors 23—23, the rearward door being pivoted or hinged adjacent the rear side wall of the frame, while the forward door 23 is hinged adjacent the cross bar 22 and which doors are of substantially the same width to close approximately one half of the frame opening. In view of the fact that both of the doors 23 are hinged in a like manner, a description of one will suffice for the other. Each door 23 is provided with end flattened pintles 24 which are disposed beneath the base flanges of angle irons 25 which are mounted along the frame, the vertical flanges of the angle iron being designated by the previously mentioned reference character 19. Engaging the under side of the flat pintles 24 are flat springs 26, one end of each spring being riveted to the frame, while the other free end is provided with a notch or groove 27 in which one of the side edges of the flat pintles 24 seat when the doors are in closed position. When the doors are swung to open position, the flat leaf springs 26 serve to clamp the pintles 24 against the under side of the angle bar or frame portions 25.

From the foregoing description it will be seen that when the doors 23 are in a closed position, they rest upon the frame 18 and therefore entirely close the frame opening, thus preventing the entrance of fresh air into a room through the screen bottom 13 of the ventilator. If it is desired to derive the full benefit of the ventilator, the doors 23 are swung to an open position substantially parallel to the downwardly inclined top wall 12 of the casing 11, whereupon the said doors permit of the free entrance of air into the room. In the event that it is desired to restrict or regulate the entrance of air, either of the doors 23 may be moved to a closed position.

While I have shown and described what I deem to be the most desirable embodiment of my invention, it is to be understood that certain of the details may be varied if desired, and I do not wish to limit myself to anything other than the whole of my invention, limited only by the appended claims.

Having thus described the invention, what I claim as new and desire to secure by Letters Patent is:—

1. In combination with a window ventilator of substantially V-shaped configuration having an inclined screen bottom wall, an air regulator including a frame supported upon said screen bottom wall, and doors hinged to said frame for shutting off the en-

trance of air through said screen bottom when said doors are in a closed position, and for regulating the flow of air therethrough by opening either or both of said doors.

2. In combination with a window ventilator of substantially V-shaped configuration 70 having an inclined screen bottom wall, an air regulator including a frame supported upon said screen bottom wall, doors hinged to said frame for shutting off the entrance of air 75 through said screen bottom when said doors are in a closed position, and for regulating the flow of air therethrough by opening either or both of said doors, and means for supporting said doors in open position.

3. In combination with a window ventilator having an inclined imperforate top wall, and an oppositely inclined screen bottom wall, an air regulator supported upon said screen bottom wall including a frame, doors 85 hinged in said frame for completely closing the frame opening when the doors are in closed position, and means for supporting said doors in an open position on a plane substantially parallel to said inclined top wall. 90

In testimony whereof I affix my signature.

VICTOR W. I. FREDERICK.
